UNITED STATES PATENT OFFICE.

GORDON E. ROEDDING AND EDWARD B. ROEDDING, OF DETROIT, MICHIGAN.

SIGNAL-LAMP.

1,259,908.

Specification of Letters Patent. Patented Mar. 19, 1918.

Application filed February 29, 1918. Serial No. 81,283.

To all whom it may concern:

Be it known that we, GORDON E. ROEDDING and EDWARD B. ROEDDING, citizens of the United States of America, residing at 5 Detroit, in the county of Wayne and State of Michigan, have invented certain new and useful Improvements in Signal-Lamps, of which the following is a specification, reference being had therein to the accompanying drawings.

This invention relates to signal devices adapted for use upon motor vehicles and more particularly to such a device embodying a rotatable sign carrying drum, and its 15 object is to provide simple and efficient electrical means for turning the drum and stopping the same in any desired position, such means having a minimum number of moving parts and being so arranged as to be 20 rigidly supported, whereby injury to the parts due to vibration is eliminated and a very compact construction secured which is not liable to get out of order and may be cheaply manufactured. A further object of 25 the invention is to provide certain other new and useful features in the construction and arrangement of parts, all as hereinafter more fully described, reference being had to the accompanying drawings in which—

30 Figure 1 is a longitudinal vertical section through a device embodying the invention;

Fig. 2 is a left hand end elevation of the same with its end cap removed;

Fig. 3 is a similar view of the right hand 35 end with the end cap removed;

Fig. 4 is a horizontal section through the device;

Fig. 5 is a transverse vertical section on the line V—V of Fig. 4;

40 Fig. 6 is a perspective detail of a drum detached;

Fig. 7 is a developed view of the shell of the drum, and

Fig. 8 is a wiring diagram showing the 45 paths of the current through the device.

In the drawings, 1 indicates a suitable casing which is preferably cylindrical in form and is provided at one side with suitable means such as a clip 2 for rigidly securing the casing to any suitable supporting bracket, and at its opposite side said casing is formed with an opening closed by glass or other transparency to form a window 3 through which a series of words or other 55 signal markings 4 on the shell of the drum may be seen. The ends of the casing are

closed by caps 6 each provided with a bull's eye and one or both of which may be made readily removable to give access to the interior of the casing.

60 The signal markings on the drum 5 consist preferably of a red transparent portion with the words "Stop" and "Slow" at one side thereof and the words "Right" and "Left" at the other side, as shown in Fig. 65 7, all of the letters of said words being also transparent and preferably white in color, the remainder of the drum being black and opaque so that the words may be readily seen at a distance during the day time and 70 all of the signals may be illuminated at night by a lamp within the drum, the red transparency permitting the use of the device as a tail light.

Rigidly secured within the ends of the 75 casing 1 are bearing brackets 7 and 8 which form rigid supports for the ends of a tube 9 fixed within and extending longitudinally of the casing at one side of or below the longitudinal axis of said casing, and the 80 brackets have upwardly extending portions or arms 10 forming supports for bearing pins 11 and 12 at the longitudinal axis of the casing, upon which pins the ends of the drum 5 are mounted to turn freely, concentrically within the casing. The drum comprises the shell having the signaling words thereon and a spider secured within each end of the shell, each spider being formed with an annular rim or ring 13 and an arm 90 14 extending radially inward to the axis of the drum to support the same and turn freely upon the pins 11 and 12.

Extending longitudinally in the axis of the drum is a driving shaft 15 which is 95 made fast at one end to one of the arms 14 of the drum so that the drum will be turned when the shaft is turned, and this shaft extends inwardly from one end of the drum to a point intermediate its ends where it is 100 supported in a suitable bearing plate 16 secured upon the tube 9. This shaft at its inner end is provided with a spiral rib 17 which extends once around the shaft and this spiral rib is engaged by a forked arm 18 105 carried by a core member which slides freely within the tube 9, said arm extending through and guided within a longitudinal slot 19 in the side of the tube.

To move the arm 18 along its slot and 110 thus by reason of its engagement with the spiral rib 17 turn the shaft 15 and its drum,

a series of electro-magnets are formed by placing solenoids 20, 21, 22 and 23 in pairs upon the tube 9, the solenoids 20 and 21 being sleeved upon the tube at one end of the slot 19 and the pair of solenoids 22 and 23 being sleeved upon the tube at the opposite end of said slot, said solenoids thus being rigidly supported in pairs upon the tube in axial alignment, with the pairs of solenoids 5 in opposed relation. This arrangement of the solenoids permits of the use of a core which is common to all of the solenoids and comprises a core member fitting and sliding freely within the tube 9 and made up of sections which are relatively movable and are connected to move together. The middle section 24 of the core carries the arm 18 and is of such a length that it extends across the space between the opposed ends of the solenoids and projects into the same for a distance at each end. The core also has end sections 25 and 26, the section 25 serving as a movable core for the solenoid 20 and the section 26 performing the function of a movable core for the solenoid 23, the core sections and solenoids thus forming electro-magnets. The end sections 25 and 26 are connected to the middle section 24 by means of rods 27 secured to the ends of the middle section at one end, and extending longitudinally through axial bores in the end sections, said rods being each provided with a head 28 to engage the outer ends of the end sections. To normally hold the end sections 20 against the heads on the rods, a coiled spring 29 is sleeved upon each rod between the adjacent ends of the end sections and the middle section.

To move the core to mid position as shown 40 in Fig. 1 and to normally hold it in that position, spring fingers 30 are secured to an insulating block 31 which is supported at one side of the tube 9 between the bearing plate 16 and a similar plate or member 82 secured upon the tube against the adjacent end of the opposed solenoid 22. The spring fingers which are secured at one end to the block 31 extend beneath and over the tube 9 and engage at their free ends the sides of 45 the arm 18 so that whenever the core 24 is moved longitudinally in either direction such movement will be resisted by one of the spring fingers, which will serve to return the core to mid position. This mid 50 or normal position of the core holds the drum 5 with the central red transparency of the drum exposed to view through the window 3 in the casing, and thus when the parts are in normal or inoperative position this red 55 signal portion of the drum only will be exposed to view and will serve the purpose of a rear tail light.

When the operator wishes to give a signal, as when he is about to turn his automobile to the left and wishes to indicate the

fact, he will by a suitable switch, button or other means not shown, energize the solenoid 22. The magnetic effect of such energization upon the middle portion 24 of the core will move said core longitudinally in the tube into the solenoid to the limit of its motion which is determined by the head of the rod 27 coming into contact with a stop plug 33 which is secured within the end of the tube 9, and thus the drum will be turned by the engagement of the forked arm 18 with the spiral rib 17 on the shaft 15 of the drum and said drum will be stopped with the word "Left" opposite the window 3 in the casing. As long as the solenoid 22 is energized, the core will be held in the position to which it has been drawn and the drum will be held in the position to which it has been turned with the signal "Left" displayed, but as soon as the current is shut off and the solenoid is deenergized one of the spring arms 30 will act to return the core and drum to mid or normal position with the red transparency again displayed.

Should the operator desire to indicate that he is about to turn to the right, this indicating signal will be made by energizing the solenoid 23. The core member 26 will be affected by such magnetization of the solenoid and will be moved endwise thereby, thus exerting a pull on the middle portion 24 of the core by reason of coming in contact with the head 28 on the rod 27. The movement which is imparted to the drum by this movement of the core member 26 will be limited by said member coming in contact with the end of the stop plug 33 and thus the signal word "Right" which is adjacent to the red signal on the drum will be aligned with the window of the casing.

Should the operator wish to indicate that he is going to stop or slow down, these words which are on the drum at the opposite side of the red transparency, may be displayed by energizing the solenoid 20 to display the word "Slow" and solenoid 21 to display the word "Stop". The drum is limited in its turning movement in this direction in the same manner in which it is limited in its turning movement in the opposite direction, that is by a stop plug 34 which is secured in the end of the tube 9 to be engaged by the head on the rod 27 and by the end of the end core member 25. With this arrangement the drum is rotated each way from a center or mid position and therefore much less power is required to turn the drum than would be required if it rotated in one direction only, as it would then be necessary to turn it nearly a whole revolution and back again to normal position. In this arrangement it is necessary to rotate it only approximately two-fifths of a revolution each way from mid position and as the drum is made of

very thin and light material, but a very small amount of power is required to turn it. Obviously more power is required to turn it to the limit of its movement in each 5 direction, that is to display the words "Left" and "Slow", than is required to display the words "Right" and "Stop", and therefore the longer movement is secured through the energization of the solenoids 21 and 22 10 which act upon the central portion 24 of the core and have a stronger magnetic effect thereon. If found desirable, buffers 35 may be provided on the brackets 7 and 8 to be contacted by the arms 14 of the drum to 15 limit the turning movement of the drum when the same is turned to the limit of its movement in either direction.

To illuminate the interior of the drum so that the signals may be readily seen at 20 night, a lamp 36 is supported by the block 31, which block is provided with suitable contacts 37 and 38 for the lamp, one of said contacts having a spring portion 39 (see 25 Fig. 5) which is in electrical contact with the tube 9, the other contact member 38 being electrically connected with the source of electrical energy through the wire 40 attached to a binding screw 41 carried by the end bracket 8. The other branch of the 30 lamp circuit comprises the spring arm 39 engaging the tube 9 which forms a conductor for the current back to the bracket 8 to which a return wire 42 is attached by means of the binding screws 43.

35 The lamp 36 is held in place upon the block 31 by means of a holder 44 which is formed with an opening to receive the lamp and has a lug 45 at its inner end to engage a notched arm 46 on the support 16, the 40 holder being extended in an opposite direction to form a long spring handle 47 adapted to be engaged beneath a suitable catch 48 and hold the lamp firmly in place. This holder also forms a suitable tool by means 45 of which the lamp may be readily inserted in the drum through the small opening in the end of the drum at one side of the arm 14.

The electrical circuits for the several 50 solenoids are indicated diagrammatically in Fig. 8, the current being carried to the solenoids 20, 21, 22 and 23 by means of wires 49, 50, 51 and 52 respectively, attached to suitable binding screws on the bracket 8. 55 The tube 9 and the wire 42 connected thereto form the return circuit for all of the solenoids.

With this arrangement of electro-magnets 60 the drum is turned by means of the fewest number of moving parts possible and the arrangement is such that it is necessary to turn the drum only a portion of a revolution each way from a mid or normal position, thus securing a saving in power and also 65 a saving in friction and consequent wear

of the parts. By supporting all of the solenoids in axial alinement upon a rigid tube and carrying the core therefor within the tube, the parts cannot be affected by vibration of the automobile in use and the liability of the parts becoming displaced or broken is reduced to a minimum. 70

Having thus fully described our invention what we claim is:—

1. In a device of the character described, 75 the combination with a movable member, of a plurality of electro-magnets within said movable member, and a common operating member for said movable member, moved different distances by the energization of 80 the different electro-magnets.

2. In a device of the character described, 85 the combination with a movable member, of opposed electro-magnets, a common core for said electro-magnets, and means includ- 90 ing a spiral member operated by the movement of said core for moving said movable member.

3. In a device of the character described, 95 the combination with a movable member, of a plurality of axially alined electro-magnets within said member, a movable core member common to all of said magnets and oper- 100 atively connected to said movable member to move the same, and means for limiting the movement of said core member to dif- 105 ferent distances of movement for different magnets.

4. In a device of the character described, 100 the combination with a signaling member, of axially alined solenoids arranged in op- 105 posed pairs, a core member common to all of said solenoids, means between the op- posed pairs of solenoids actuated by said core to turn said signaling member, and means in said solenoids for limiting the movement of the core member to turn the signaling member different distances.

5. In a device of the character described, 110 the combination with a signaling member having a driving shaft; of opposed electro- 115 magnets, having a common core reciprocable in parallelism with said driving shaft and adapted to impart a rotary movement there- 120 to, and means for returning said core to normal position upon de-magnetization of said core.

6. In a device of the character described, 120 the combination with a movable signaling member, of a spiral member carried by said signaling member, opposed electro-magnets having a common core, means engaging said spiral member for transmitting motion from the core to said movable member, and means for yieldingly holding the core in mid position.

7. In a device of the character described, 125 the combination with a rotatable signaling member, of opposed solenoids arranged in axial alinement, a movable core common to

both of said solenoids, means including an arm for transmitting motion from the core to turn the signaling member, and a spring engaging both sides of said arm to normally hold the core member in mid position.

8. In a device of the character described, the combination of a casing, a rotatable drum in the casing, opposed electromagnets supported by the casing within the drum, a drum shaft extending longitudinally of the drum at its axis and at one side of said magnets, means for yieldingly holding the drum in mid position, and means for transmitting motion from the electromagnets to the shaft for turning the drum in each direction from its mid position.

9. In a device of the character described, the combination with a rotatable drum having signal markings thereon, of a plurality of solenoids arranged in axial alignment, a movable core common to all of said solenoids, means including an arm and spiral member for transmitting motion from the core to turn the drum, and means for limiting the movement of the core to different distances according to the number of solenoids.

10. In a device of the character described, the combination with a rotatable signaling member, of a plurality of axially aligned solenoids, a movable core common to all of said solenoids and comprising relatively movable parts, and means for limiting the movements of the parts of said core to turn the signaling member different distances, said core being operatively connected with said signaling member to turn the same.

11. In a device of the character described, the combination of a rotatable drum having signal markings thereon and arranged to display one of said markings when the drum is in normal position and to display the other markings when the drum is turned in either direction from its normal position, means for yieldingly holding the drum in normal position, electromagnets wholly within the rotatable drum at one side of the axis thereof for turning the drum different distances from its normal position in one direction and other electromagnets for turning the drum different distances from its normal position in an opposite direction.

12. In a device of the character described, the combination of a rotatable drum having

signal markings thereon and arranged to display one of said markings when the drum is in normal position and to display the other markings when the drum is turned in either direction from its normal position, a casing inclosing the drum, brackets in the end of the casing, and electrical means supported by said brackets wholly within the drum for turning the drum.

13. In a device of the character described, the combination of a rotatable drum having signal markings thereon and arranged to display one of said markings when the drum is in normal position and to display the other markings when the drum is turned in either direction from its normal position, a casing inclosing the drum with its ends adjacent the open ends of the drum, a spiral member fixed to rotate with said drum, electrical means wholly within the limits of the drum for actuating said spiral member to turn said drum, and means at the ends of the casing for supporting the drum and electrical means.

14. In a device of the character described, the combination of a rotatable drum having signal markings thereon, a casing inclosing the drum, brackets in the ends of the casing, electrical means within the drum supported by said brackets adapted to turn the drum in each direction from a normal position, and means within and axially of said electrical means for stopping the drum in different positions during its turning movement.

15. In a device of the character described, the combination of a casing, a rotatable drum in the casing having a plurality of signal markings, electromagnets in the drum adapted to operate to turn the drum different distances, said electromagnets being disposed longitudinally of the drum and having a common movable core, said core being made up of relatively movable sections, and stops to limit the movement of the core sections to limit the turning movement of the drum.

In testimony whereof we affix our signatures in presence of two witnesses.
